SOCKET FOR STARTER UNITS FOR
FLUORESCENT LAMPS

Joseph O. Howard, Chicago, Ill., assignor of one-half to Peter J. Franklin, Chicago, Ill.

Application December 16, 1946, Serial No. 716,631

4 Claims. (Cl. 173—328)

1

This invention pertains to sockets and receptacles for electrical equipment having pin contacts, such, for example, as starter units for fluorescent lamps, and the like.

One of the principal objects of the invention is the provision of a socket structure which may be manufactured from an assembly of punchings and stampings from sheet stocks of both metal and insulating materials.

Viewed from another aspect, it is an important object of the invention to provide an economically manufactured socket of rugged structural quality and highly satisfactory electrical characteristics, which can be made as an assembly item from punchings and stampings of flat stocks, and which requires none of the expensive and frequently breakable molded parts commonly found in sockets of the type described.

Additional objects are, specifically, the provision in a socket structure of insulating wafers supporting contacts therebetween by tongue and slot formations, with channel-shaped spacers between the wafers, or certain of them, and in a certain offset relationship to the contacts, for holding certain wafer elements in position by slotted engagement therewith, and for maintaining other wafer elements in position by tongue and slot engagement therewith, as well as securing the whole in assembled condition, all as more particularly revealed hereinafter.

The foregoing, as well as additional objects and aspects of novelty, relate to structural and functional details of the novel socket and the embodiment thereof to be described in view of the annexed drawing in which:

Fig. 1 is a perspective view of a fluorescent lamp fixture of a type with which the novel socket is adapted to be used;

Fig. 2 is a vertical cross section, to enlarged scale, of a portion of said lamp fixture and the novel socket structure therein, other parts being shown in elevation;

Fig. 3 is a transverse cross section along lines 3—3 of Fig. 2;

Fig. 4 is a top plan view of the socket;

Fig. 5 is a horizontal section through the socket;

Fig. 6 is a fragmentary view of the contact end of a lamp starter of the type adapted to be mounted in said socket;

Fig. 7 is a perspective detail of one of the contact arms;

Fig. 8 is a vertical section through the socket along lines 8—8 of Fig. 5.

Referring to Fig. 8, the socket structure is as-

2

sembled from thin wafers of insulating material, suitably stamped and punched in particulars hereinafter appearing, there being a pair of lower wafers 10 and 11, and a pair of upper wafers 12 and 13, the shape of these wafers being that of the top-most wafer 13 as it appears in Fig. 4.

Between the upper and lower sets of insulating wafers or plates aforesaid, is an intermediate guide wafer 14, Fig. 8, supported rigidly by and 10 between a pair of channel spacers 15 stamped from sheet metal, said spacers being of substantially U-shaped cross section with clinching lugs or ears 16 projecting from the ends thereof and clinched over onto the outermost wafers of the 15 top and bottom sets as shown in Figs. 4 and 8, the latter showing only one of said spacers, while the former figure shows the ears turned over onto the top-most wafer 13.

Said channel-shaped spacers are punched to 20 provide aligned slots in the regions 17 thereof to receive the thickness of the intermediate guide wafer 14, as in Fig. 8, said wafer having opposite tongue portions 18 fitting into the channel portion of the corresponding spacers, so that said 25 intermediate or guide wafer is securely supported in a position about midway between the upper and lower sets of wafers, said guide wafer 14, as in Figs. 4 and 5, having a pair of elongated, slightly arcuated contact pin slots 19 disposed 30 about a center therein, and each said slot being provided with an enlarged terminal portion 19A to receive the correspondingly enlarged head portions 20 of the contact pins on the starter unit 21 shown in Fig. 6.

35 The two upper wafers 12 and 13 are punched to provide registering circular openings 22, Fig. 4 to receive the base portion of the starter unit 21 so that the contact pins 20 of the latter may be 40 inserted into the enlarged terminal portions 19A of the slots in the guide wafer, said starter thereafter being turned to lock the contacts thereof with certain contact arms to be described.

The contact arms are formed as exemplified in Fig. 7, wherein a stamping of brass or other conductive material is shown to include a body portion 25 perforated and tapped at 26 to receive screw 27 (Fig. 8) by which a conductor is attached to the arm, an edge portion 28 of said body or root portion of the contact arm being 50 struck up to afford a stop for additionally confining the conductor in connection with said screw.

Important to the mounting of the contact arms in the socket are tab or ear portions 29 formed 55 integrally with the body or root portion and re-

spectively fitting into slots punched in the innermost wafer of each said pair or set, as illustrated in Fig. 8; in other words, wafers 11 and 12 are provided with slots to receive said tab portions 29 on the contact arms, but the outermost wafers 10 and 13 are not provided with such slots, although both sets of wafers, that is to say, both wafers of each pair or set, are punched to permit passage therethrough of the clinching ears 16 on the channel spacers.

Extending from the root or body portion of each contact is an offset or curved arm portion 30 provided with a contact-locking crimp or notch 31, Figs. 5 and 7, into which the contact pins 20 of the starter unit snap when the starter is turned home after the headed portions of said starter contacts are fitted into the enlarged terminal portions 19A of the pin slots, Fig. 4, the relative disposition of said locking notches 31 and the arcuate pin slots 19 appearing especially in Fig. 4.

It will now appear that the novel socket structure may be readily assembled from simple and inexpensive punchings and stampings of ordinary sheet stock, and that in its completed form the socket comprises a pair of upper and lower wafers rigidly connected in parallel spaced relation by channel spacers crimped into the respective pairs, a pair of contact arms being firmly seated between said pairs by engagement of tabs thereon in punched formations in the innermost wafer of each said pair, there being further an intermediate guide wafer slotted to guide contact pins relative to the contact arms.

It will be appreciated that the outermost wafer of each said pair or set might be omitted, and the contact arms could be maintained in position by clinching of the spacer channel onto upper and lower wafers, only; however, this arrangement is not commercially desirable if the wafers are to be inexpensively stamped from the relatively thin stock necessary for economical punching and stamping operations, additional strength being afforded by the laminated structure shown, utilizing at least two wafers in the upper and lower sets.

The novel socket is readily adapted to, and mounted in, a standard lighting fixture of the type illustrated in Fig. 1, which includes a base or box portion 49 generally mounted on the ceiling and having opposite lamp sockets 41 pendent therefrom to mount an elongated tubular lamp 42 of the fluorescent variety, requiring a starter element such as the device 21 heretofore alluded to, a portion of which is shown protruding from the base of the lamp fixture in Fig. 1.

One of the lamp sockets 41 is shown in Fig. 2, the same preferably being of the construction disclosed in my copending patent application Serial No. 716,630, filed December 16, 1946, a feature of which is the mounting bracket of channel shape, indicated at 43 and attached to said socket by lugs 44 as a means for securing in position certain cover plate parts (not illustrated) of the socket while at the same time affording a means for mounting the lamp socket on the fixture, as by screw 45, said channel shaped mounting bracket further affording a means for mounting the starter socket in position, one side portion of said channel bracket being punched to permit passage therethrough of the clinching ears 16 at one end of one of the channel spacers 15 of the starter socket, Figs. 2 and 3.

The novel socket structure is rugged enough to withstand considerable abuse in shipping, in-

stallation, and use; no molding dies are required, and those stamping and punching dies which are utilized in manufacturing the wafers, contacts, and spacers, are of quite simple and inexpensive nature; moreover, the sheet stock or insulation material, as well as the metal stock for the contact arms and spacers, is commonly used in great quantities in industry and is normally quite cheap and available and is of such character, along with the methods by which the parts are struck off, to facilitate large-scale manufacture of the sockets by highly economical methods.

Certain objects, advantages, and aspects of novelty and utility peculiar to the improved socket structure have been emphasized in conjunction with the disclosure herein of specific forms and details of one commercial embodiment of the invention, but it is to be understood that the scope of the invention is not intended to be limited by such specific recitations; that the invention is intended to include modified and variant forms of embodiment described within the ambit of the appended claims and features of improvement originating with this description and disclosure.

I claim:

1. A socket comprising parallel insulating wafers spaced apart in parallelism by at least two channel spacers each having lugs in opposite ends thereof and clinchingly engaged with a wafer member at the corresponding end thereof, a pair of contact arms disposed in the space between said wafers and secured in position by tab projections thereon engaged in slot formation in said wafers, and an intermediate guide wafer disposed in the region between said parallel wafers and adjacent said contact arms, said intermediate wafer having portions supportably interfitting with recessed and slot portions of said spacers, and contact guiding openings in said intermediate wafer.

2. In a socket structure, a pair of upper wafers and a pair of lower wafers of insulating material, a pair of channel shaped spacers between said pairs of wafers, each spacer having lugs at its ends passing through the wafers at the corresponding ends and struck over to secure said pairs of wafers in parallelism, an intermediate wafer between said pairs and secured in position by interfit with slot formations in said spacers, a pair of contact arms disposed between one pair of wafers and said intermediate wafer and each arm having a root portion spanning the distance between said pairs of wafers at a point spaced from one of said spacers, to maintain the pairs of wafers in spaced relation cooperatively with said spacers, each said root portion having a pair of tabs, each of said tabs being fitted into a slot in the innermost one of the wafers of one of said pairs to hold said contact arms in position, said intermediate wafer being formed to permit spanning of the root portions across the space between the pairs of wafers as aforesaid, said intermediate wafer having openings to guide contact pins relative to said contact arms, one pair of said wafers having a passage therethrough for reception of a socketed member having contact pins for engagement with said contact arms, said channel members and said root portions being disposed in quadrangular array and affording four-point support for said pair of wafers.

3. A socket comprising insulating wafers of approximately rectangular form, a pair of spacers of U-shaped cross section between said wafers and having lugs at their respective ends clinched

over through said wafers to secure the latter in spaced parallelism, a pair of contacts disposed between said wafers and each having tab and slot supporting engagement with said wafers, said spacers being offset on opposite sides of the longest axis of said wafers and one of each of said contacts being positioned on a side of said axis opposite one of said spacers, said contacts having root portions spanning the distance between said parallel wafers to maintain the latter in spaced relation cooperatively with said spacers, a guide wafer having interfitted tongue and notch engagement with said spacers, with openings for guiding contact elements relative to said contacts.

4. In a socket structure, top and bottom plates spaced apart at the axially opposite ends of channel-shaped spacers therebetween, said spacers having endwise ears clinched into corresponding plates, each spacer having a side opening facing in a general sense toward the side opening in the other, and an intermediate plate supported, between said top and bottom plates, by tongue formations thereon projecting

into said side openings of each spacer together with body portions adjoining said tongue formations fitted into slot formations in said spacers, said tongue formations preventing displacement of the intermediate plate in a direction laterally of the axis between said opposite ends, and said portions in the slot formations preventing displacement in the direction of said axis and said opposite ends, contact means between said top and bottom plates, and contact guide formations in said intermediate plate.

JOSEPH O. HOWARD.
